UNITED STATES PATENT OFFICE

CARLEY GOULD WELD, OF NORTH CHATHAM, MASSACHUSETTS.

DESIGN FOR A CASING FOR FLUID-MOTIVE POWER-PUMPS AND CONNECTIONS.

43,241.

Specification for Design.

Patented Nov. 5, 1912.

Application filed August 6, 1912. Serial No. 713,682. Term of patent 3½ years.

To all whom it may concern:

Be it known that I, CARLEY GOULD WELD, a citizen of the United States, residing at North Chatham, in the county of Barnstable and Commonwealth of Massachusetts, have invented a new, original, and ornamental Design for a Casing for Fluid-Motive Power-Pumps and Connections, of which the following is a specification, reference being had to the accompanying drawing, forming a part thereof.

The said drawing is a side or perspective view of a fluid motive power pump made in accordance with my new design.

I claim—

The ornamental design for casing for fluid motive power pumps and connections as shown.

In witness whereof I have hereunto set my hand in the presence of two subscribing witnesses, this 3rd day of August, 1912.

CARLEY GOULD WELD.
